(57) CLAIM

The ornamental design for a vaginal dilator, as shown and described.

DESCRIPTION

FIG. 1 is an upper perspective view of the vaginal dilator according to a first embodiment;

FIG. 2 is a right side elevational view thereof, the left side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is an upper perspective view of the vaginal dilator according to a second embodiment;

FIG. 8 is a right side elevational view thereof, the left side being a mirror image;

FIG. 9 is a front elevational view thereof;

FIG. 10 is a rear elevational view thereof;

FIG. 11 is a top plan view thereof;

FIG. 12 is a bottom plan view thereof;

FIG. 13 is an upper perspective view of the vaginal dilator according to a third embodiment;

FIG. 14 is a right side elevational view thereof, the left side being a mirror image;

FIG. 15 is a front elevational view thereof;

FIG. 16 is a rear elevational view thereof;

FIG. 17 is a top plan view thereof;

FIG. 18 is a bottom plan view thereof;

FIG. 19 is an upper perspective view of the vaginal dilator according to a fourth embodiment;

FIG. 20 is a right side elevational view thereof, the left side being a mirror image;

FIG. 21 is a front elevational view thereof;

FIG. 22 is a rear elevational view thereof;

FIG. 23 is a top plan view thereof;

FIG. 24 is a bottom plan view thereof;

FIG. 25 is an upper perspective view of the vaginal dilator according to a fifth embodiment;

FIG. 26 is a right side elevational view thereof, the left side being a mirror image;

FIG. 27 is a front elevational view thereof;
FIG. 28 is a rear elevational view thereof;
FIG. 29 is a top plan view thereof; and,
FIG. 30 is a bottom plan view thereof.

The broken lines in the drawings are for the purpose of illustrating portions of the vaginal dilator that form no part of the claimed design in the embodiments in which they are shown.
